UNITED STATES PATENT OFFICE.

FRANCIS C. DICKSON, OF LOUISVILLE, KENTUCKY, ASSIGNOR OF ONE-HALF TO
GARNETT S. ZORN, OF LOUISVILLE, KENTUCKY.

APPARATUS FOR CLEANING GRAIN.

1,207,512.

Specification of Letters Patent.

Patented Dec. 5, 1916.

Application filed January 26, 1916. Serial No. 74,323.

To all whom it may concern:

Be it known that I, FRANCIS CULLODEN DICKSON, a citizen of the United States, residing in the city of Louisville, county of 5 Jefferson, and State of Kentucky, have invented certain new and useful Improvements in Apparatus for Cleaning Grain, of which the following is a specification.

This invention relates to apparatus for 10 cleaning grain, with more particular reference to its applicability to removing smut from wheat or other edible cereals.

An object of this invention is the provision of a process whereby smut, and the peculiar 15 odor thereof, as well as the other objectionable odors such as those due to the presence of wild onions, may be thoroughly removed.

Smut is a parasitic fungus which grows 20 upon many kinds of grain, various species of which have an offensive odor, on account of which they are known as "stinking smut." Smut clings very tenaciously to its host, a portion only thereof being removed in the process of threshing. A very small percentage 25 of smutted wheat in a shipment lessens its market value, while any considerable quantity of smut renders a shipment unmarketable. Many expedients resorted 30 to, to clean smut from grain, have met with partial success only, as smut pores lie in the kernel furrows, from whence it is difficult 35 to dislodge them. I have discovered that if wheat, or other grain is agitated in a suitable acidulated bath, the smut will be completely removed, and its characteristic odor 40 destroyed. I have found that a halogenous acid is preferable, and that hydrochloric acid, (the muriatic acid of commerce) gives the best results, an aqueous solution containing 45 from two to fifteen per cent. of acid being used, the strength of the solution varying with the condition of the grain. After treatment in the acid bath, the grain is treated with clear water to rinse away all 50 traces of the acid; it is then dried. It will then be clean, free of odor, and will grade A 1.

Another object is the provision of an apparatus whereby said process may be carried 55 on continuously and which will give a maximum output with a minimum of expense.

A further object is the provision of apparatus for carrying out said process which will be economical in construction and efficient and durable in service.

With the foregoing and other objects in

view, the invention consists of the novel construction and arrangement of parts illustrated in the accompanying drawings, wherein is set forth an embodiment of the 60 invention, but it is to be understood that such changes and modifications may be resorted to as come within the scope of the appended claims.

Referring to the drawing wherein similar 65 reference characters designate like parts throughout the several views, Figure 1, is a side elevation of an embodiment of the apparatus, parts being broken away to show the construction; Fig. 2, is a top plan; Fig. 70 3, a rear end elevation; Fig. 4, a front elevation; Fig. 5, an end elevation of the agitator shaft; Fig. 6, a side elevation, on an enlarged scale, of a portion of the agitator shaft; Fig. 7, a side elevation of one of the 75 agitator blades.

In the embodiment of the apparatus as illustrated herewith—the reference character —11— designates a "slosh" tank of suitable construction which is supported by 80 legs —12—. A sloping bottom —13— leads to a semi-circular trough, or conveyer box —14—. An agitator shaft —15— suitably mounted within the box 14 extends exteriorly thereof and is provided with a sprocket 85 wheel —16— by means of which motion may be imparted to the shaft. Within the box, a plurality of flights, or blades —17—, adjustably secured on the shaft, serve to thoroughly agitate, or "slosh" about the 90 contents, while at the same time moving it forward, longitudinally of the trough. The center portion of the flights, or blades is cut away leaving an opening —18—, and the angle of inclination of the flight, relative to 95 the axis may be varied. The tank discharges through a conduit —19— into an inclined conveyer —20—. Water is introduced into the tank, from a suitable source of supply by means of a pipe —21—, and the acid is admitted through a pipe —22—, from a suitable receptacle as —23—. It is obvious that the proportions of acid and 100 water admitted into the tank, may be regulated respectively by means of valves —24—, 105 —25—. The height of the liquid in the tank, is limited by an overflow pipe —26— which leads to a suitably located filter —27—. A circulating pump —28— serves to return the liquid, after filtration, to the tank by way 110 of a pipe —29—. The connection between the tank and the conveyer is water tight con-

sequently the liquid rises in the conveyer 20, to the same level as in the tank. Grain from a suitable source of supply is led into the tank by means of a conduit. —32—, which leads down into the tank and delivers the grain direct into trough 14. A plurality of baffle plates —30, 31— are suitably positioned in the tank. Grain is delivered direct to the conveyer, in the trough and at one end thereof, in order that the inflowing grain may not interfere with the movement of the grain in the tank. The arrangement of the flights 17 is such as to "slosh" or agitate thoroughly the contents of the tank, imparting a forward and rotary movement to the grain which sends it upward and forward through the surrounding liquid. In their movement the kernels strike the baffle plates and are deflected thereby causing them to collide with the other kernels. The attrition thus produced, together with the detergent action of the liquid, completely removes the smut and the odor thereof is destroyed by the chemical reaction. The circular movement of the grain causes the separation of any husks, or lighter seeds, such as those of wild onion, which aided by an upward current of the liquid, caused by the circulating pump, ascends to the surface and passes off through the overflow, to the filter.

When the grain reaches the far end of the trough, it drops through the chute 19, into the inclined conveyer 20. The conveyer 20 is of a type well known to the art, and is not thought to require more extended description than to say that it comprises a cylindrical shell —33— within which is mounted a shaft —34— carrying a spiral flight —35—. The shaft 34 is provided exteriorly of the conveyer tube, with a bevel gear —36—. The under side of the tube 33 is provided with a plurality of perforations —37— which extend longitudinally upward for a spaced distance from the point to which the liquid, from the tank, rises. These perforations are for the purpose of allowing adhering liquid to drain from the grain. A false bottom, or pocket —38— is disposed under the perforations to catch the drainage, and overflow, and lead it to a drainage pipe —39— which connects with the pipe 26 which leads to the filter. When the grain reaches the upper end of the conveyer —20— it descends through a chute —40— into a horizontal conveyer —41— wherein the acid solution is rinsed off of the grain. The horizontal conveyer is similar to the inclined conveyer, comprising a cylindrical shell —42—, within which is mounted a shaft —43— which carries a spiral flight —44—. The shaft 43 extends exteriorly of the conveyer and is provided with a sprocket wheel —45—. A spray pipe —46— is disposed within the horizontal conveyer, above the

spiral flight, extending longitudinally thereof, and is supplied with water, from a suitable source, by means of a pipe —47—. The under side of the shell of the horizontal conveyer is provided with perforations —48— 70 which permit of the escape of the rinsings. False bottoms, or pockets —49, 50— are disposed under the perforations and lead the rinsings to the drain pipes —51, 52—. When the grain reaches the far end of the 75 horizontal conveyer it is entirely free of acid, and here it is discharged into a chute —53— which delivers it into an Archimedean conveyer —54—. This style is likewise well known to the art and needs no extended 80 description. It comprises a cylindrical shell —55— which is revolved bodily, the shell being supported on rollers —57—, and receiving motion by means of a sprocket —58— which encircles the shell. A spiral 85 flight —56— is secured to the inner surface of the shell. This conveyer is pitched slightly downward from the entrant end. Heated air, conducted from a suitable source 90 of supply, through a pipe —60—, is forced into the conveyer 54 at the exit end thereof, and in its passage therethrough takes up all the moisture clinging to the passing grain. The action of the Archimedean conveyer is such that the grain is being constantly rolled 95 over and over and shifted in position so that every portion of it is subjected to the action of the current of heated air. Grain is discharged from this conveyer into a chute —61— by which it may be led to any desired 100 depository. The various mechanisms receive motion from a main driving shaft —62—, on which is mounted a pulley —63— by means of which power is imparted to the shaft from a suitable source (not shown). Secured on the main shaft are sprocket 105 wheels —64, 65—, from which, through suitable mediums as —66, 67— motion is transmitted respectively to the sprocket 58 on the Archimedean conveyer and the 110 sprocket 45 on the shaft 43. A bevel gear —68— transmits motion from the main shaft to a transverse shaft —69—. Secured on the transverse shaft are sprocket wheels —70, 71—. A suitable medium as —72— 115 leading from the sprocket 70 transmits motion to a sprocket —73— secured on a counter-shaft —74— and a bevel gear —75— meshes with the bevel gear 36 on the shaft 34 in the inclined conveyer 20. A suitable 120 medium —76— leads from the sprocket 71 on the transverse shaft 69 to the sprocket 16 on the agitator shaft 15. The circulating pump is actuated by a belt —77— leading from a pulley —78— on the transverse 125 shaft 69. In starting, water is admitted to the tank until it reaches the overflow, then the valve 24 is opened and acid admitted until the solution reaches the desired strength. Power is then turned on, and the agitator 130

blades thoroughly stir the mixture. Grain is then admitted through the feed spout 32. The water valve 25 is adjusted to admit sufficient water to make good the loss of what is 5 carried off by the grain—and the acid valve is adjusted to admit the amount necessary to maintain the solution at the desired strength. As the condition of the grain varies the strength of the solution may be increased or decreased accordingly by admitting more or less acid. Extraneous substance such as husks, wild onions, or other matter which rise to the surface of the solution in 10 the tank, may be skimmed off or allowed to 15 pass off with the overflow and removed from time to time from the filter.

It is thought that the foregoing description is sufficient to enable anyone skilled in the art pertaining thereto, to utilize my improved process, and to construct and operate 20 the apparatus described herein for putting the process into practice.

Having thus described my invention so that anyone skilled in the art pertaining 25 thereto may make and use the same I claim:

1. In apparatus for desmutting and deodorizing smutted grain, a tank for containing cleansing fluid, a filter, an overflow pipe leading from the tank to the filter, means 30 for returning the fluid to the tank after filtration, an inclined tube containing a conveyer which leads from a point directly below the tank to a point above the same, a fluid tight connection between the tank and 35 the tube whereby the fluid stands at the same level in both tank and pipe, a horizontal tube containing a conveyer, a connection leading from the upper end of the inclined tube to said horizontal tube, a second 40 horizontal tube into which the aforesaid horizontal tube discharges, and means for directing a current of air through the last named tube.

2. In apparatus for desmutting and deodorizing smutted grain, a tank for containing cleansing fluid, a filter, an overflow pipe, leading from the tank to said filter, means for returning the fluid to the tank after 45 filtration, an inclined tube which extends from a point below the tank to a point above the same, a fluid tight connection between the tank and said tube, a second tube, and a connection leading from the upper end of the inclined tube to the second named tube.

3. In apparatus for desmutting and deodorizing smutted grain, a tank for containing cleansing fluid, a filter, an overflow pipe, leading from the tank to said filter, means for returning the fluid, to the tank after 50 filtration, an inclined tube which extends from a point below the tank to a point above the same, a fluid tight connection be-

tween the tank and said tube, a second tube, a connection leading from the upper end of 65 the inclined tube to the second named tube, a third tube into which the second named tube discharges, means for introducing grain into the tank, means positioned respectively in the tank, and tubes for moving 70 the grain therethrough, the floor of the upper portion of the inclined tube being perforated whereby the grain is drained as it is passed over the same, and means for conducting the drainage to the filter. 75

4. In apparatus for desmutting and deodorizing smutted grain, a tank for containing cleansing fluid, a filter, an overflow pipe, leading from the tank to said filter, means for returning the fluid to the tank after 80 filtration, an inclined tube which extends from a point below the tank, to a point above the same, a fluid tight connection between the tank and said tube, a second tube, a connection leading from the upper end of 85 the inclined tube to the second named tube, a third tube into which the second named tube discharges, means for introducing grain into the tank, means positioned respectively in the tank, and tubes for moving 90 the grain therethrough, the floor of the upper portion of the inclined tube being perforated whereby the grain is drained as it is passed over the same, means for conducting the drainage to the filter and a 95 spray pipe, within the second named tube for rinsing the grain.

5. In apparatus for deodorizing and desmutting smutted grain, a tank, baffle plates positioned therein, semi-circular depressions 100 in the bottom of said tank, a shaft revolvably mounted therein, a plurality of flights on said shaft, an inclined tube which extends from a point below the tank to a point above the same, a fluid tight connection between 105 the tank and said tube, a helical conveyer in said tube, a second tube, a helical conveyer therein, a spray pipe disposed in said second tube, and an Archimedean conveyer into which the second tube discharges. 110

6. In apparatus for desmutting and deodorizing smutted grain, a tank, baffle plates positioned therein, semi-circular depressions in the bottom of said tank, a shaft revolvably mounted therein, a plurality of flights on said shaft, an inclined tube which extends from a point below the tank, to a point above the same, a fluid tight connection between the tank and said tube, a helical conveyer in said tube, a second tube, a helical conveyer therein, a spray pipe disposed in said second tube, an Archimedean conveyer into which the second tube discharges, and means for directing a current of air through the last mentioned conveyer. 115 120 125

FRANCIS C. DICKSON.
